UNITED STATES PATENT OFFICE.

WILLIAM J. HAMILTON, OF KENMORE, NEW YORK, ASSIGNOR OF ONE-HALF TO PAUL C. DUNNING, OF BUFFALO, NEW YORK.

HUNTING BOOT.

Application filed February 2, 1927. Serial No. 165,436.

This invention relates to boots worn by sportsmen, lumbermen, and others, and to methods of making same. This class of boot is usually formed with a lower foot portion 5 formed of rubber or other water-proof material and an upper of relatively light material such as leather, and in which a tongue or closure extends between and is connected to the fastening edges, eyelet strips or lac- 10 ing edges and has its bottom edge secured to said bottom or foot portion to form a substantially water-proof boot.

Such boots are usually of the blucher type, 15 in which the front edges of the uppers, provided or formed with fastening means are extended down upon the lower or foot part and have their front edges free and spaced apart. In some of these constructions the bottom edges also of said strips are free, 20 while in others they are stitched down, with the bottom edges of the upper, to the top edge portion of the bottom member. In this manner the lower portion of the tongue or closure member which extends across the 25 instep is left unprotected and as this member is usually made of relatively thin and soft leather or material, it soon wears out, due to the exposure to moisture and dirt and the excessive flexing and hard wear to which 30 this part of the boot is subjected. Furthermore, the detached lower portions of the eyelet strips usually extend away more or less from the boot, and when worn in the 35 woods, often catch on snags or sticks, causing discomfort and possible injury to the wearer.

The principal object of the present invention is to provide an improved boot constructed to overcome the above objections, 40 and whereby the cost of production will compare favorably with that of boots of ordinary construction and whereby the boot can be produced without increase in material or number of parts.

Further objects are to provide an improved boot of this character wherein the lower portions of the front edges of the upper converge towards and meet or are connected to each other so as to extend 45 across the front of the boot in front of the lower portion of the tongue or closure to protect this part from excessive wear and exposure to dirt and water.

It has heretofore been thought necessary 50 to form the lower portion of the tongue or

closure with considerable fullness in one way or another in order that the foot may be easily inserted into the boot, and this extra material must be gathered or bunched over the instep when lacing the boot, to the consequent discomfort of the wearer and creasing and deterioration of the tongue. In such constructions, in order to provide the necessary fullness aforementioned, the portion of material forming the tongue or closure has been formed of substantially the same width at the bottom as at the top thereof.

Another object of the invention is to provide an improved boot in which the last 5 named objections are eliminated and in which the lower portions of the upper and tongue are so formed that when the boot is laced, said portion of the tongue will lie flat and smooth beneath the adjacent portions of the upper, and in which nevertheless ample room is provided for inserting the foot into said boot. Another object of the invention is to provide an improved method 60 of producing boots of the class mentioned, whereby the foregoing results may be obtained; and also to improve hunting boots and methods of making the same in the other respects hereinafter set forth and claimed.

In the accompanying drawings, Fig. 1 is a perspective view of a hunting boot embodying the invention.

Fig. 2 is a front view of the tongue or closure member connected to the front edges 90 or eyelet strips of the uppers, showing the same before the lower portions of said strips are secured together.

Fig. 3 is a fragmentary, horizontal section through the upper front portion of the 95 boot with the parts laced.

Fig. 4 is a fragmentary face view of the upper of the boot in condition for attachment to the lower or foot portion thereof.

Fig. 5 is a fragmentary, horizontal section looking upwards, approximately on line 5—5, Fig. 4.

Fig. 6 is a fragmentary perspective of the front portion of the boot as it appears when laced.

Fig. 7 is a fragmentary elevation showing the inner face of the connected lower portions of the tongue and one of the quarters of the upper.

Fig. 8 is an elevation of the inner face 110

of the lower portion of the tongue and the adjacent portions of the upper, and a portion of the attached lower or foot part of the boot.

The hunting boot embodying the invention and shown in the drawings includes the usual bottom member or foot part 10, which preferably comprises a vamp 11, and a sole and heel portion 12 of rubber vulcanized together to form a single unitary member of water-proof construction. Secured to the periphery or top edge portion 10^a of this member 10 is the upper 13 composed of the opposite side pieces or quarters 14, back stay 15 and tongue or closure member 16. The side pieces 14 have their front edges constructed to form the usual eyelet strips, lacing stays 17 or other fastening means, and the edge portions 18 of the tongue preferably extend across these strips and are secured to the inner and outer edges thereof by rows of stitches 19. The edges or strips 17, instead of being arranged in spaced and substantially parallel relation at their lower ends as in previous constructions, are, in accordance with this invention made to converge towards each other and are connected at their lower ends in front of the tongue 16 to cover and protect this portion.

In forming the upper, the lower front portions of the quarters 14 are lasted or otherwise shaped so as to extend forwardly, and the edges of the tongue 16 are secured to the edges or strips 17 thereof as shown in Fig. 2. The lower corners of said strips are preferably left projecting downwardly slightly beyond the straight, bottom edge 20 of the tongue so as to provide projecting tabs 21. These tabs 21 are brought together and secured preferably by abutting or lapping along their adjacent edges and securing these edges by stitching 23 passing through and over, as shown clearly in Figs. 4-6. When this has been done, the tongue or closure member is folded as shown in Figs. 5 and 8, so as to lie flat against adjacent portions of the upper, after which the upper is positioned with its lower edge portion 23^a extending around and engaging the outer face of the corresponding upper peripheral or edge portion 10^a of the bottom member 10, and with the lower, straight edge portion 20 of the tongue and the connected edges of the strips 17 extending down upon said edge portion of the member 10. When thus assembled, the upper 13 and bottom member 10 are secured together, preferably by cement and parallel rows of stitching 24, which are carried across the seam or stitching 23, so that this seam is flattened down as much as possible.

As shown in Fig. 2, the outer side edges of the tongue or closure member 16 converge toward each other from top to bottom so that

the lower portion of this member is of considerable less width than the upper portion thereof. Thus the shape of the tongue corresponds to the form or converging arrangement of the front edges of the quarters 14, 70 and the tongue will fold smoothly and without wrinkles when the boot is laced, while ample room is nevertheless provided for the insertion of the foot.

The boot constructed as described, is very 75 neat and attractive. The novel form of the lower parts of the quarters and closure member or tongue gives ample room for the insertion of the foot, and the tongue lies flat and smooth beneath the adjacent portions of the upper, and the converging and meeting lower edge portions of the eyelet strips or edges 17 protect the lower portion of the tongue. Furthermore, when laced, the front edges of the upper extend upwardly relatively close together from the seam 23, and eliminate all gaps likely to engage obstructions, thus providing an anti-snag boot.

While as shown, the lower portions of the edges or strips 17 are extended below the bottom edge 20 of the tongue for the purpose of reducing the thickness of the seam 23 formed by the meeting edges of said strips, the tongue can, if desired, be extended all the way down to the bottom edge 95 of the upper.

I claim as my invention,

1. In a boot of the character described, a 100 foot part having a peripheral top edge, an upper having its bottom edge extending about and secured to said edge of said foot part and having opposed front fastening edges, a tongue extending between and having its side edges secured to said edges of 105 said upper, and said upper having its opposite, lower front portions formed to converge across and substantially meet in front of the lower portion of said tongue to protect the latter.

2. In a boot of the character described, a 110 foot part having a peripheral top edge, an upper having its bottom edge extending about and secured to said edge of said foot part and having opposed front fastening edges, a tongue extending between and having its side edges secured to said edges of 115 said upper, said upper having its lower front edge portions extending toward each other and secured together over the lower portion of said tongue, and said secured portions of said edges and said lower portion of said tongue being also secured to said top edge of said foot part.

3. In a boot of the character described, a 125 foot part having a peripheral top edge, an upper having its bottom edge extending about and secured to said edge of said foot part and having opposed front fastening edges, a tongue extending between and hav- 130

ing its side edges secured to said edges of said upper, said edges having their lower portions secured together in front of the lower portion of said tongue to cover and 5 protect the same, and said lower portions of said edges and tongue being also secured to said top edge of said foot part.

4. In a boot of the character described, a foot part having a peripheral top edge, an 10 upper having its lower edge extending about the upper edge of said foot part and having opposed front fastening edges, a tongue extending between and having its side edges stitched to said edges of said upper, said 15 edges having contacting portions at their lower ends which are stitched together in front of the lower portion of said tongue, and said lower edge of said upper, said contacting portions of said edges and said lower 20 portion of said tongue being stitched to said top edge of said foot part.

5. In a boot of the character described, a foot part having a peripheral top edge, an upper having its lower edge extending about 25 the upper edge of said foot part and having opposed front fastening edges, a tongue extending between and having its side edges stitched to said edges of said upper, said edges having contacting portions at their 30 lower ends which are secured by a seam in front of the lower portion of said tongue, said lower edge of said upper, said contacting portions of said edges and said lower portion of said tongue being secured to the 35 upper edge of said foot part by continuous stitching extending around said boot, and passing across said seam.

6. In a boot of the character described, a foot part having a peripheral top edge, an 40 upper having its lower edge extending about the upper edge of said foot part and having opposed front fastening edges, a tongue extending between and having its side edges stitched to said edges of said upper, contacting portions at the lower front ends of 45 said upper which are secured together in front of the lower portion of said tongue and extend partly below the same upon said top edge portion of said foot part, and said 50 contacting portions of said upper and said lower portion of said tongue being also secured to said edge of said foot part.

7. In a boot of the character described, a foot part having a peripheral top edge, an 55 upper having its lower peripheral edge secured to said edge of said foot part, said upper having opposed fastening edges at the front thereof which converge and are connected at their lower ends, a tongue extending between and having its side edges

secured to said edges of said upper and which is formed to converge correspondingly with said edges, whereby said tongue will lie smooth beneath said edges when laced, and said connected parts of said edges and 65 the corresponding part of said tongue being also secured to the top edge of said foot part.

8. A method of constructing a hunting boot having a foot part, an upper including a pair of opposed fastening edges, and a tongue, which consists in securing the side edges of said tongue to said edges of said upper, securing the lower portions of said edges together in front of the lower portion 70 of said tongue, and finally securing the lower edge portion of said upper, said secured portions of said edges and said lower portion of said tongue to the top edge of said foot part.

9. A method of constructing a hunting boot having a foot part, an upper including a pair of opposed fastening edges, and a tongue, which consists in stitching the opposite side edges of said tongue to said edges of said upper while said latter edges are 80 spaced apart, and stitching together the 85 lower portions of said edges in front of the lower portion of said tongue, and finally stitching the lower edge portion of said upper, said engaging portions of said edges and said lower portion of said tongue to 90 the upper edge of said foot part.

10. A method of constructing a hunting boot having a foot part, an upper including a pair of opposed fastening edges, and a tongue, which consists in securing the side edges of said tongue to said edges of said upper, securing the lower portions of said edges together in front of the lower portion of said tongue, and finally securing the lower edge portion of said upper, said secured portions of said edges and said lower portion of 95 said tongue to the top edge of said foot part by continuous rows of stitching passing around said boot.

11. In a boot of the character described, a 100 waterproof foot part formed of rubber or the like material and having a peripheral top edge, an upper formed of leather and having its bottom edge extending about and secured to said edge of said foot part and 110 having opposed fastening edges, and a tongue extending between and secured to said edges, and said upper having its opposite lower front portions extended forwardly across and meeting in front of the 115 lower portion of said tongue, and said meeting portions of said upper and said lower portion of said tongue being also secured to said top edge of said foot part.

WILLIAM J. HAMILTON.
